FORMING DIE

James A. Exline, Jr., Miamisburg, Ohio

Application December 23, 1949, Serial No. 134,652

2 Claims. (Cl. 153—76)

1

This invention relates to a method and apparatus for forming shallow metal articles, such as a dish, by folding or bending the metal of which the article is formed in a predetermined pattern.

When forming shallow articles from metal sheets, it is the conventional practice to place a metal sheet between male and female dies for drawing the metal to the desired configuration. This conventional practice necessitates accurate and expensive production of metal dies.

It is therefore an object of this invention to provide a method and apparatus for forming shallow metal articles to a predetermined design configuration by bending or folding a metal sheet to a predetermined pattern in a single operation.

It is another object of the invention to provide a method and apparatus for forming a metal sheet into a predetermined pattern in a single operation by forcing a metal sheet between spaced stationary elements to cause the sheet to bend or fold form in a predetermined pattern.

It is still another object of the invention to provide a machine tool for producing the results of the foregoing objects.

It is another object of the invention to provide a machine tool for fold forming or bending a metal sheet in which the metal sheet is clamped between moveable members and the sheet is thereafter moved against stationary members to cause it to bend at selected locations on the sheet to produce an article of predetermined shape by a bending operation.

It is another object of the invention to provide a forming die in which a metal sheet is clamped between a die cushion and a plunger and is thereafter moved against stationary members while clamped between the die cushion and plunger to cause the sheet to bend in predetermined portions of the sheet to bend form or fold form the sheet to a predetermined pattern.

Further objects and advantages will become apparent from the drawings and the following description.

Figure 1 is a perspective view of a dish formed by the method and apparatus of this invention.

Figure 2 is a plan view of the forming die of this invention.

Figure 3 is a vertical cross-sectional view of a forming die taken along line 3—3 of Figure 2.

Figure 4 is a vertical cross-sectional view like Figure 3 but illustrating the die in operation in forming the article illustrated in Figure 1.

Figure 5 is a vertical cross-sectional view of a modified form of the die illustrated in Figure 3.

Figure 6 is a plan view of a portion of the die illustrated in Figure 5.

2

Figure 7 is a vertical cross-sectional view of another modified form of the die.

Figure 8 is a plan view of the die illustrated in Figure 7.

5 Figure 9 illustrates another modified form of the die.

Figure 10 is a perspective view of a portion of the die illustrated in Figure 9.

10 Figure 11 is a cross-sectional view of the portion of the die illustrated in Figure 10.

In this invention the forming die consists of a base 10. An annular ring 12 is positioned upon the base 10 and is suitably secured thereto, as by the cap screws 13.

15 A die cushion 14 is positioned on the axis of the ring 12, and internally of the ring. This die cushion 14 may be of a square shape as illustrated in Figure 2, or may be round if desired. The die cushion 14 is supported upon guide studs 15 placed at each corner of the die cushion 14. A compression spring 16 is placed around each of the guide studs 15 to maintain the die cushion 14 in the position illustrated in Figure 3.

The lower ends of the guide studs 15 are provided with enlarged heads 17 that move within recesses 18 provided in the base 10, the head 17 limiting the upward movement of the die cushion 14. The top surface 19 of the die cushion 14 is positioned slightly above the level of the top surface 20 of the ring 12 so that a metal sheet or disc 21 placed upon the die cushion 14 will be clamped between the bottom surface 22 of a plunger 23 and the top surface 19 of the die cushion 14 before the metal sheet or disc 21 engages the ring 20 in its downward movement into the ring, thus positively locating the disc 21 on the die cushion before any forming is performed on the disc 21.

40 A plurality of pins 25 are spaced circumferentially around the axis of the ring 12 and are positioned between the inner surface 26 of the ring 12 and the die cushion 14, as illustrated in Figure 3. While the pins 25 are illustrated as being independently mounted on the base 10, yet

45 the structure can be in the form of a ring positioned within the ring 12 with the pins 25 projecting upwardly therefrom. The pins 25 are spaced equi-distantly on a common circle about the axis of the ring 12 so that downward movement of the disc 21 onto the pins 25 will cause the pins to contact the disc at equi-distantly spaced points about the circumference of the disc. Also, the pins 25 are radially equi-distant from the axis of the ring 12 so that they contact the disc 21 radially equi-distantly upon downward

movement of the disc 21 into contact with the pins 25.

To locate the metal disc 21 co-axially with the ring 12 a plurality of locating pins 27 are carried on the upper edge surface 20 of the ring 12.

The plunger 23 may be a part of any pressure applying device, such as a hand operated arbor press or a mechanical or hydraulic press, the purpose of the plunger 23 is to clamp the disc 21 between the plunger and the die cushion 14 and to urge the disc 21 downwardly into the ring 12 and upon the pins 25. The diameter of the lower end 28 of the plunger 23 is equal to the diameter and shape of the portion of the disc 21 that will be unformed or unbent, this portion forming the bottom wall of the dish or receptacle 30 illustrated in Figure 1.

The pins 25 are spaced radially outwardly of the outer periphery of the lower portion 28 of the plunger 23 to engage the disc 21 at points spaced from the engagement of the outer periphery of the portion 28 of the plunger 23 with the disc 21 so that engagement of the disc 21 with the pins 25 will cause a bending inwardly of the disc at each point of engagement when the plunger 23 moves the disc 21 downwardly, as shown in Figure 4 on the left hand side of the illustration. The portions of the disc 21 that are intermediate the point of contact of the pins 25 with the disc 21 will bend reversely of the portions contacted by the pins 25 so that the reversely bending portions 31 contact the inner corner edge 33 of the ring 12, and thereby control the reverse bending of these portions of the disc 21. The inwardly bending portions 32 cooperate with the outwardly bending portions 31 to provide a fluted side wall for the receptacle 30 as illustrated in Figure 1.

It will be understood that the spaced arrangement of the pins 25 on their circle of engagement with the disc 21 can be altered circumferentially and radially to vary the contour of the receptacle 30. Also, the particular construction of the die illustrated in Figures 2 to 4 can be modified without effecting the spirit of this invention.

Thus, in Figures 5 and 6 there is illustrated a slightly modified form of the construction illustrated in Figures 2 to 4 in that the pins 25 are replaced by lugs 25a that project from the ring 12a. In all other respects the die illustrated in Figures 5 and 6 is the same as that previously described, and its operation is the same so that common parts of the two devices carry the same reference numeral but with the suffix "a."

In Figures 7 and 8 there is illustrated another modified form of the die in which the ring 12 illustrated in Figure 3 is omitted. In the form of the die illustrated in Figures 7 and 8 the pins 25b and the die cushion 14b are constructed the same as previously disclosed and described with reference to Figure 3, thus like parts carry like numerals but with the suffix "b."

To replace the ring 12 of the die illustrated in Figure 3, a plurality of posts 40 are provided in the device shown in Figures 7 and 8. These posts 40 are spaced intermediate adjacent pins 25b as illustrated in Figure 8 so that the outwardly bending portions 31 of the receptacle illustrated in Figure 1 will contact the upper corner edges 41 of the posts 40 and thereby control the outward bending of these portions in

the same manner the ring 12 controls this bending in the device illustrated in Figure 3.

In Figures 9 and 10 there is illustrated a slightly modified arrangement of the construction of the upper ends of the pins 25 illustrated in Figure 3 to reduce the friction between the disc 21 and the pins 25 when the pins slide along the disc as it is urged downwardly between the pins 25 as shown in Figure 4.

The pins 25c, as shown in Figures 9 and 10, include a socket 50 at the upper ends of each of the pins 25c that receives a ball 51. The ball 51 is held in the socket 50 by a retainer 52.

Since the ball 51 is free to rotate in the socket 50, friction between the disc 21c and the ball 51 will be less than the friction between the disc 21 and the pin 25 shown in Figure 3, and thus reduce any tendency of the pin 25 to mark the surface of the disc 21 as it slides over the ends of the pins.

While the devices disclosed and described illustrate preferred arrangements of the device and its method of forming a receptacle, yet it will be understood that modifications can be made without departing from the spirit of the invention, as illustrated, and that modifications that fall within the scope of the appended claims are intended to be included herein.

Having thus fully described my invention, what I claim as new and desire to secure by Letters Patent is:

1. In a forming die, a base, a die cushion, resiliently acting means between said base and said cushion supporting said cushion on said base and for resisting movement thereof relative to said base, a plurality of stationary rod-like members positioned circumferentially about said cushion in radially spaced relationship thereto each extending vertically and having a limited work contact surface thereon, at the upper end and wall means carried on said base positioned circumferentially about said cushion at a distance radially greater than said stationary members and having an upwardly facing work contact surface thereon disposed at substantially the level of the work contact surfaces on said stationary members.

2. In a forming die, a base, a die cushion, resiliently acting means between said base and said cushion supporting said cushion on said base and for resisting movement thereof relative to said base, a plurality of stationary rod-like members positioned circumferentially about said cushion in spaced relationship thereto each extending vertically and having a limited work contact surface thereon, and an annular stationary ring carried on said base positioned about said cushion at a distance radially greater than said stationary members and having a work contact surface on the upper edge thereof disposed substantially at the level of the work contact surfaces on said stationary members.

JAMES A. EXLINE, JR.
